UNITED STATES PATENT OFFICE

172,196

ARROWHEAD

Lowell W. Roper, Oakland, Calif.

Application October 12, 1953, Serial No. 27,155

Term of patent 7 years

(Cl. D34—15)

To all whom it may concern:

Be it known that I, Lowell W. Roper, a citizen of the United States, residing at Oakland, in the county of Alameda and State of California, have invented a new, original, and ornamental Design for an Arrowhead, of which the following is a specification, reference being had to the accompanying drawing, forming part thereof.

Figure 1 is a side elevational view of an Arrowhead showing my new design;

Figure 2 is a top plan view;

Figure 3 is a front end elevational view thereof; and

Figure 4 is a rear end view of the same.

I claim:

The ornamental design for an arrowhead, as shown.
